UNITED STATES PATENT OFFICE.

WILLIAM J. SCHLACKS, OF CHICAGO, ILLINOIS, ASSIGNOR TO MCCORD AND COMPANY, OF CHICAGO, ILLINOIS, A CORPORATION OF DELAWARE.

RATCHET DRIVE.

1,288,692.

Specification of Letters Patent. Patented Dec. 24, 1918.

Application filed March 27, 1918. Serial No. 225,038.

To all whom it may concern:

Be it known that I, WILLIAM J. SCHLACKS, a citizen of the United States, residing at Chicago, in the county of Cook and State of Illinois, have invented certain new and useful Improvements in Ratchet Drives; and I do hereby declare the following to be a full, clear, and exact description of the invention, such as will enable others skilled in the art 10 to which it appertains to make and use the same.

My present invention has for its object to provide an improved ratchet drive for converting reciprocatory or vibratory motion 15 into a rotary movement, and to such ends, generally stated, the invention consists of the novel construction and combination of parts hereinafter described and defined in the claims.

20 The improved ratchet drive is especially designed for and adapted to use in connection with a force feed lubricator for converting the vibratory movement of an engine driven arm into a rotary movement required 25 to slowly operate eccentric driven pumps.

The improved ratchet drive in its preferred form shown as applied to a force feed lubricator is illustrated in the accompanying drawings wherein like characters indicate 30 like parts throughout the several views.

Referring to the drawings:

Figure 1 is a view in side elevation with some parts broken away and some parts sectioned, showing the ratchet drive applied to 35 the lubricator; and

Fig. 2 is a vertical section taken approximately on the line 2—2 of Fig. 1, some parts being shown in full.

The numeral 3 indicates the oil tank of 40 the lubricator, the same at one end having a detachable head 4 formed with a bearing sleeve 5 equipped with a stuffing box 6. Inward of the head 4, the tank 3 is formed with an inner wall 7 that is spaced from said 45 head 4 to form a chamber 8 for the ratchet mechanism. Said wall 7 is formed with a large bearing sleeve 9, the axis of which is concentric to the axis of the sleeve. The oil pumps 10 which are of a well known plunger 50 type have their plungers connected to drive heads 11 carried by vertically movable frames 12 that are subject to eccentrics 13 carried by a rotary shaft 14. The construction and operation of these pumps need

not be considered further than to state that 55 the said pumps will be slowly operated under rotation of the shaft 14. This shaft at one end has an enlarged head 15 journaled in the bearing sleeve 9 and having a projecting annular flange to which, as shown, a cylindrical rim 16 is rigidly secured by threaded engagement, or otherwise. This rim 16 has internal ratchet teeth 17 and external ratchet teeth 18 which for an important reason, hereinafter noted, are odd in number; to 60 illustrate, the ratchet teeth 17 may be fifty-five in number and the ratchet teeth 18 may be seventy-five in number.

Extended through the stuffing box 6 and journaled in the sleeve 5 and in an axial seat 70 in the head 15 is an oscillatory shaft 19 to the outer end of which an arm 20 is rigidly secured. This shaft 20 will, in practice, be connected to some vibratory part of the locomotive or engine. 75

The oscillatory shaft 19 inside of the cylindrical ratchet toothed rim 16 is provided with a diametrically projected drive head 21 which in its opposite ends has cylindrical seats into which are fitted cylindrical driving dogs 22. These dogs 22 at their outer ends are provided with ratchet teeth that extend transversely across the outer end surfaces thereof, and in size correspond to the internal ratchet teeth 17 with which they are 80 engageable. The central of the teeth of these ratchet dogs are, of course, wider than the forward and rearward teeth and, in fact, are approximately as wide as the said internal teeth 17. Width is herein used to mean the 85 longitudinal extent of the teeth in a direction parallel to the axis of the ratchet device.

The said cylindrical dogs 22 are made hollow to receive coiled compression springs 23 90 that are compressed between the same and the solid intermediate portion of the head 21, and yieldingly press said dogs outward into engagement with the coöperating internal ratchet teeth 17. 100

For engagement with the external ratchet teeth 18 I provide two retaining dogs. These retaining dogs are preferably of approximately the same construction as the driving dogs 22, and are located at diametrically opposite points in respect to the axis of the ratchet device. The said retaining dogs 24 are cylindrical and hollow and they 105

are mounted in cylindrical seats 25 afforded by tubular portions 26 cast integral with the outer side walls of the tank 3 and with a cylindrical interior web 27 which, in turn, 5 is cast integral with the wall 7 and closely surrounds the ratchet rim 16.

Springs 28 are seated in the retaining dogs 24 and are compressed between the same and plugs 29 which latter are shown as screwed 10 into the outer ends of the tubular portions 26. With the above described construction it is not only possible, but entirely feasible, even where considerable energy is transmitted, to make the ratchet teeth 17 and 18 15 and the coöperating ratchet teeth of the driving and retaining dogs small. These numerous small teeth will provide as great, or greater strength, than a very much larger tooth in an arrangement wherein but one 20 tooth is acted upon at a time. The small ratchet teeth, of course, give a much finer movement than larger teeth, and this is an important consideration in locomotive lubricators where fine adjustment of the pumping 25 action is required.

Moreover, the cylindrical dogs afford wide teeth or teeth that are long in a direction parallel to the axis of rotation of the ratchet device. As the dogs are cylindrical and 30 capable of rotation in their seats, the teeth of the dogs will adapt themselves to the teeth of the ratchet rim and will effect a full and complete or parallel tooth engagement. This insures a long working life of even 35 very fine ratchet teeth.

It may now be noted that inasmuch as the two driving dogs 22 are located diametrically opposite to each other and inasmuch as the coöperating internal ratchet teeth 17 40 are odd in number, it will follow that when the one ratchet dog is in full engagement or driving action on the said ratchet teeth 17, the diametrically opposite dog 22 will have its teeth positioned midway between 45 the points of the engaged ratchet teeth 17. Thus a fineness of adjustment or driving action is obtained that is equal to one-half the circumferential space between adjacent teeth 17. Also, since the external teeth 18 are 50 odd in number and the retaining dogs are diametrically opposite, the above noted fineness of adjustment holds good for these retaining dogs.

The diametrically opposite arrangement 55 of the driving dogs and retaining dogs and their coöperating seats also facilitates accurate and cheap construction, for instance, the seats for the retaining dogs are axially alined and may be bored or reamed by one 60 operation. As the springs are telescoped into the dogs, very compact construction is provided. In the ratchet drive of the character above described, the oscillatory driving head may be oscillated to and fro 65 through angles varying from 360° or a com-

plete rotation to that very slight movement represented by one-half the circumferential space between adjacent ratchet teeth.

By referring to Fig. 1 it will be noted that the head 4 when removed permits the 70 driving shaft 19 and its head to be readily removed without opening up the interior of the oil tank and without permitting the escape of any oil from the said tank. Moreover, the bore of the sleeve 9 is of such 75 size that the driven shaft 14 and its eccentrics 12^a may be removed axially from the tank but this, of course, will open the tank for the escape of oil. The said arrangement, of course, also permits the shaft 14 80 and its eccentrics to be readily placed in working position after the eccentrics have been assembled and properly secured on said shaft.

It may be further noted that when the 85 plugs 28 are removed, the retaining dogs 24 may be removed from working position without opening up the tank or permitting the escape of oil therefrom.

As a minor but important feature of the 90 invention, the threaded engagement between the head 15 and the rim 16 is such that under the driving action or force transmitted therethrough by the driving dogs, said rim will be kept screwed onto the head as far as 95 it will go, thus insuring the rim against becoming loose from the head under continued use.

What I claim is:

1. A ratchet drive comprising an oscillatory driving shaft and a co-axial rotary driven shaft, said driven shaft having an internally and externally ratchet toothed rim, and said driving shaft having a head located within said rim, diametrically opposite spring pressed driving dogs seated in said driving head and operative on the internal teeth of said rim, and diametrically opposite spring pressed retaining dogs operative on the external teeth of said rim. 100

2. A ratchet drive comprising an oscillatory driving shaft and a co-axial rotary driven shaft, said driven shaft having an internally and externally ratchet toothed rim, and said driving shaft having a head located within said rim, diametrically opposite spring pressed driving dogs seated in said driving head and operative on the internal teeth of said rim, and diametrically opposite spring pressed retaining dogs operative on the external teeth of said rim, the internal threads of said rim being odd in 115 number and the external threads of said rim also being odd in number. 120

3. A ratchet drive comprising an oscillatory driving shaft and a co-axial rotary driven shaft, said driven shaft having an internally and externally ratchet toothed rim, and said driving shaft having a head located within said rim, diametrically op- 125

posite spring pressed driving dogs seated in said driving head and operative on the internal teeth of said rim, and diametrically opposite spring pressed retaining dogs operative on the external teeth of said rim, the said dogs each having a multiplicity of ratchet teeth and being capable of rotation to permit their teeth to adapt themselves to full engagement with the coöperating ratchet teeth of said rim.

4. A ratchet drive comprising an oscillatory driving shaft, a rotary driven shaft, said driven shaft having an enlarged cylindrical end formed with a seat in which the end of said driving shaft is journaled, an internally and externally ratchet toothed rim rigidly secured to the head of said driven shaft, a head on said driving shaft located within said ratchet toothed rim, a driving dog carried by the head of said driving shaft and operative on the internal teeth of said rim, and a relatively stationary retaining dog operative on the external teeth of said rim.

5. A ratchet drive comprising an oscillatory driving shaft, a rotary driven shaft, said driven shaft having an enlarged cylindrical end formed with a seat in which the end of said driving shaft is journaled, an internally and externally ratchet toothed rim rigidly secured to the head of said driven shaft, a head on said driving shaft located within said ratchet toothed rim, diametrically opposite outwardly spring pressed rotatively mounted driving dogs carried by the head of said driving shaft and each having a multiplicity of teeth operative on the internal ratchet teeth of said rim, and diametrically opposite spring pressed rotatively mounted retaining dogs each having a multiplicity of teeth operative on the external ratchet teeth of said rim.

6. A ratchet drive comprising an oscillatory driving shaft, a rotary driven shaft, said driven shaft having an enlarged cylindrical end formed with a seat in which the end of said driving shaft is journaled, an internally and externally ratchet toothed rim rigidly secured to the head of said driven shaft, a head on said driving shaft located within said ratchet toothed rim, diametrically opposite outwardly spring pressed rotatively mounted driving dogs carried by the head of said driving shaft and each having a multiplicity of teeth operative on the internal ratchet teeth of said

rim, and diametrically opposite spring pressed rotatively mounted retaining dogs each having a multiplicity of teeth operative on the external ratchet teeth of said rim, the internal and external ratchet teeth of said rim being odd in number for the purpose set forth.

7. The combination with a tank having a detachable head and formed adjacent to said head with a ratchet inclosing chamber having a large bearing sleeve opening into said tank, an oscillatory driving shaft journaled in said head, a driving shaft having a head journaled in said large bearing sleeve and provided within said tank with eccentrics of less diameter than said bearing sleeve, the head of said driven shaft having a seat in which the inner end of said driving shaft is journaled, an internally and externally threaded ratchet toothed rim secured to the head of said driven shaft and located within said ratchet housing, the said rim being removable from said housing when the head of said tank is removed, a driving dog carried by said driving shaft and operative on the internal teeth of said rim, and a retaining dog mounted in a wall of said housing and operative on the external teeth of said rim.

8. A ratchet drive comprising an oscillatory driving shaft and a co-axial driven shaft, said driven shaft having an internally and externally threaded ratchet rim, said driving shaft having a head located within said rim, a plurality of self adjusting driving dogs rotatively seated in said head, and operative on the internal ratchet teeth of said rim, and a plurality of retaining dogs operative on the outer ratchet teeth of said rim.

9. A ratchet dog comprising an oscillatory driving shaft and a co-axial rotary driven shaft, said driven shaft having a ratchet toothed rim secured thereto by threaded engagement, the threaded engagement being such that it will be tightened by the driving force, and said driving shaft having a dog equipped head operating on said rim.

In testimony whereof I affix my signature in presence of two witnesses.
